OIL REMOVER OR WIPER WITH BUILT-IN
OIL CATCHING RECEPTACLE

Samuel Friedman, Brooklyn, N. Y.

Application February 2, 1949, Serial No. 74,053

19 Claims. (Cl. 15—236)

1

This invention relates to a device for removing or wiping oil from the hand or hands of a machine mechanic or operative.

The prime object of my present invention centers about the provision of a device capable of functioning effectively for removing films or coatings of oil covering the hand or hands of a mechanic or operative tending oil consuming or using machines such as automatic screw machines, turret lathes and the like. In my Patent No. 2,425,526 of August 12, 1947, I disclose such a device which is characterized by the following structural and functional features:

1. It is capable of performing its function of removing or wiping off the oil films or coatings covering and adhering to the hands of the mechanic, with thoroughness and efficiency.

2. It does not involve wastage of material and may be used and re-used almost indefinitely for the purpose.

3. It may form a fixture made, for example, in the shape of a machine attachment so that it is always located in a known position, handy and ready for use.

4. It may be so constructed and designed as to oil-clean all parts and surfaces of the hands of the operative.

5. It may be used with great rapidity and satisfying convenience and may be made at an exceedingly low cost.

In actual use, the device of said previously issued patent has proved extremely effective to attain the desired objectives. However, it has been found that when such a device is used over a period of time, the oil or grease which is wiped from the operative's hand by the device accumulates on the device, and particularly on the exterior surfaces thereof, and eventually covers not only the device, its supporting bracket and the machine or other article to which the bracket is affixed, but also eventually drips down to the floor, thus not only increasing the difficulty involved in maintaining the premises in a clean condition but also increasing the likelihood of slipping, thus making working around the machine a more hazardous task. The result is both unsightly and unsanitary.

It therefore has been found desirable to modify the construction disclosed in the previously issued patent so as to provide means on the interior of the wiper for collecting the oil and grease which is wiped from the hands of the user, thus preventing the accumulated oil and grease from escaping onto the equipment or the floor and facilitating disposal or reuse of the

2

wiped oil or grease. Not only does this make the wiper more sanitary and the surroundings cleaner, but also, by confining the wiped waste material to an enclosed receptacle, eliminates the possibility that, by reason of accidental contact, said waste material might soil the hands or clothing of passers-by.

As pointed out in the previously issued patent, the wiper is most convenient in use when three wiping blades are presented for use, one for wiping the back of the hand, one for wiping the palm of the hand, and one for wiping the fingers. However, as is pointed out in said previously issued patent, an effective wiper can be constructed formed of only two wiping blades, one for the fingers and the other for the back and the palm of the hand. The present invention is specifically disclosed in the three-blade form, two of the blades coacting with additional structural elements so as to define the receptacle which stores the wiped oil or grease but, as pointed out in the previously issued patent, a construction involving only two wiping blades also comes within the scope of the present invention.

By reason of the structural coaction between two of the blades so as to define a receptacle, it is possible to form the wiper integrally as by means of a one-piece casting, thus reducing the cost of production and at the same time giving rise to a more attractive unit which is possessed of the above described advantages, and this without sacrificing any of the functional attributes set forth in said previously issued patent.

It is therefore an object of the present invention to devise a hand wiper which is more pleasing in appearance and more sanitary and economical in use than the previous embodiments thereof.

Yet another object is to devise such a hand wiper which is so constructed and arranged that the oil or grease wiped from the hand of the operative is caused to collect in a receptacle from which it may conveniently be dispensed for disposal or reuse.

A still further object of the present invention is to devise such a wiper which is adapted to be secured in an operative position on a bracket, the bracket being secured to a machine or other object, the wiper being capable of ready removal from the bracket in order to facilitate disposal of the wiped oil or grease which has collected therein. If desired, the wiper may be secured to a bucket or pail without having to use a special bracket.

To the accomplishment of the foregoing objects and such other objects as may hereinafter appear, the present invention relates to an improved oil remover or wiper as defined in the appended claims and as described in this specification, taken together with the accompanying drawings, in which:

Fig. 1 is a perspective view showing how the device may be attached to the head of a turret lathe or the like;

Fig. 2 is a front elevational view of the wiper of the present invention;

Fig. 3 is a side cross-sectional view taken along the line 3—3 of Fig. 2;

Fig. 4 is a top view thereof;

Fig. 5 is a rear elevational view thereof;

Fig. 6 is a side cross-sectional view similar to Fig. 3 but showing the wiper secured to the bracket and illustrating one mode of use of the wiper; and

Fig. 7 is a view similar to Fig. 6 but showing another mode of use thereof.

The oil removing device of the present invention comprises a plurality of wiper blades generally designated A, B and C so constructed and spatially arranged that the operative, by one continuous sweep of either hand over the device, may effectively wipe or scrape off all of the oil adhering to one side of the hand and by a second continuous sweep of the hand over the device may effectively wipe or scrape off all of the oil adhering to the other side of the hand.

A receptacle generally designated D is defined between two of the wiper blades, here shown as the blades A and B, the receptacle D being adapted to catch all of the oil or grease as it accumulates until it is desired to dispose of the same. Troughs generally designated E and E' are provided on the exterior of the wiper blades A and B respectively, the trough E' being defined by the blade C, and communicating passages F are provided between the troughs E and E' and the receptacle D so that oil or grease which runs down the outer surfaces of the wiper blades A and B or the inner surface of the blade C will find its way into the receptacle D.

The wiper of the present invention will preferably take the illustrated form of a one-piece unit which may be conveniently formed in a single casting operation. Such a construction has the advantage that the unit is seamless and consequently the possibility of leakage of oil or grease is almost entirely eliminated. It is, however, definitely within the scope of the present invention to make the wiper of a plurality of units assembled together.

The intermediate wiper blade B terminates in an upwardly disposed wiping edge 2 which is recess-shaped as may best be seen in Fig. 2 so as to be provided with four recesses or concave depressions 4 shaped to receive and fit part-way around the individual four fingers of either of the operative's hand. The side surfaces 6 of the wiper blade B are also curved so as to fit part-way around the fifth finger of the operative's hand.

The wiper blade A terminates in an upwardly disposed wiping edge 8 which is line-shaped and which may, if desired, take the slightly curved form illustrated in the drawing. It is the edge 8 which is particularly adapted to scrape the palm of the operative's hand. The wiper blade A is provided at its sides with two raised portions 10 which serve the dual purpose of scrap-

ing the sides of the operative's hand and of guiding his hand as it is being swept across the blades A and B.

The wiper blade C terminates in an upwardly disposed wiping edge 11 which may be slightly concave in shape as viewed from above (see Fig. 4), this edge 11 being particularly adapted to scrape the back of the operative's hand. It will be noted that the edge 11 is disposed somewhat below the wiping edges 2 and 8 of the wiping blades B and A respectively, this arrangement being preferred in order to facilitate use of the device as described hereinafter.

These wiper blades A, B and C are relatively arranged and spaced so as to carry out the functions above described and best illustrated in Figs. 6 and 7 of the drawing. These three blades are also secured together so as to form one operative unit or tool. More specifically considered, the blades A and B are so spatially arranged and the edges 2 and 8 are so relatively disposed that with one continuous sweep of the hand the surfaces of the palm and front of the operative's hand are oil-wiped, and when the operative's hand is inverted and then swept across the blades B and C, the surfaces of the other side of his hand are oil-wiped.

The blades A and B extend upwardly from and are connected to a first wall 12 in the form of a base and side walls 14 and 16 extend upwardly from the first wall 12 and between the blades A and B. Consequently, an enclosed space which constitutes the receptacle D is defined between the blades A and B, the first wall 12 and the side walls 14 and 16. It will be apparent that any oil scraped from the operative's hand by the interior surface of the wiper blades A or B will run down along that interior surface into the receptacle D. However, it often happens, as will be explained more in detail hereinafter, that oil is wiped from the operative's hand along the exterior surface of the blade A or B. In order to ensure that this oil is also led to the receptacle D, troughs E and E' are formed on the exterior surfaces of each of the blades A and B, the trough E being defined by the lip 20 connected at its bottom and sides to the blade A, and the trough E' being defined by the lip 18 connected at its bottom and sides to the blade B, the lip 18 terminating in the wiping edge 11 and hence also defining the wiping blade C, and orifices 22 and 24 are formed respectively in the wiper blades A and B at the bottom of the troughs E and E' so that any oil and grease which is caught by the troughs E and E' will pass into the receptacle D, the orifices 22 and 24 thus constituting the communicating passages F.

Depending from the first wall 12 are a pair of arms 26 and 28 spaced from one another so as to fit over the upstanding end 30 of a bracket 32 which is adapted to be secured in any appropriate manner to a turret lathe or any other piece of machinery 34 in connection with which the use of the wiper is desired. The arms 26 and 28 are appropriately apertured as at 36 and 38, the aperture 36 being internally threaded so as to receive wing-screw 40 the portion 41 of which is externally threaded. If, as here disclosed, the upstanding portion 30 of the bracket 32 is provided with an aperture 42, the portion 41 of the wing-screw 40 will pass through that aperture and be received in the aperture 38 in the arm 28, thus securing the device to the bracket 32. On the other hand, if it be desired to position the device on the non-apertured upstanding rim of a bucket or pail, the inward tip of the wing-screw

40 will press against the outer surface of said rim, cause the arm 28 to be drawn against the inner surface of the rim, and thus secure the device thereto. In this way, the wiper may be positioned in close proximity to the piece of equipment which causes the operative's hands to become soiled or to any other appropriate object. At the same time, the wiper is readily detachable therefrom when it becomes necessary to dispose of the accumulated oil or grease which collects in the receptacle D.

The use and manner of functioning of the wiper will in the main be fully apparent from the above description. Figs. 6 and 7 disclose a preferred manner of use. The operative's hand 44, palm down, may first be swept in the direction of the arrow 46, the operative's palm first passing over the wiping edge 8 on the wiper blade A and the oil or grease on the operative's palm being scraped off therefrom by the wiping edge 8 and passing down along the exterior surface of the blade A into the trough E, and from the trough through the apertures 22 in the blade A into the receptacle D, where it accumulates. As this single sweep of the operative's hand continues, the base of his fingers will come opposite the wiping blade B, at which time the operative will fit his fingers into the recesses 4 and as he continues to sweep his hand in the direction of the arrow 46, the grease or oil will be wiped from the bottom and sides of his fingers 48 and will flow along the interior surface of the wiper blade B into the receptacle D. The first part of this movement, in which the operative's palm is scraped, is illustrated by the broken lines in Fig. 6, and the second part of this movement, in which the operative's fingers are scraped, is illustrated by the solid lines.

The operative's hand is next inverted so that the back of the hand is down and the hand is then swept in a single direction as indicated by the arrow 50 in Fig. 7, the direction of sweep being such that the back of the operative's hand first passes over the wiping edge 11 on the wiper blade C, the oil or grease on the back of the operative's hand being scraped off therefrom and passing along the interior surface of the blade C into the trough E' and thence through the aperture 24 in the blade B into the receptacle D. As this sweep is continued, the base of the operative's fingers will come opposite the wiping edge 2 of the wiper blade A and hence the back of his fingers may be scraped clean in the same manner as were the front of his fingers as disclosed in Fig. 6.

The above described method of use is one which has proved to be most convenient, but the wiper can, of course, be used in many other ways. For example, if only the blades A and B are to be used for wiping purposes, both the front and the back of the operative's hand may be scraped clean as disclosed in Fig. 6 or, if desired, the direction of sweep of the operative's hand may be opposite to that specifically disclosed in the drawing. It will be apparent that no matter which way the blades are used, the grease or oil scraped from the operative's hand will ultimately collect in the receptacle D and will not give rise to any of the unsightly and unsanitary conditions previously pointed out as characteristic of the unimproved wiper. The only qualification which need be placed on the above statement is that the blade C should not be used with a sweep direction opposite to that disclosed in Fig. 7, for if it were, the scraped oil or grease

would pass along the exterior of the wiper and thus eliminate the advantages inherent in the present invention. Of course, even this limitation would be avoided if an additional trough were provided on the exterior of the blade C, but that has not been found necessary in most applications.

By reason of the above described construction, the wiper of the present invention may be used for a long period of time without any care or supervision, without in any way giving rise to deterioration in the conditions of cleanliness prevailing at the time and in the vicinity in which the wiper is used. The wiped oil or grease cannot drip from the wiper or flow from it along the bracket 32 onto the machine 34 or onto the floor beneath. The wiper may be readily removed from the bracket 32 for cleaning purposes or for disposal of the oil or grease which has accumulated inside the receptacle D merely by removing the wing-screw 40, but this need not be done very frequently. The entire unit is very pleasing in appearance, is substantial in construction, may in its preferred form be inexpensively manufactured in a single casting operation, has no moving parts to get out of order, and efficiently performs its desired function.

It will be apparent that many variations may be made in the precise construction of this device 30 all within the spirit of the invention as defined in the following claims.

I claim:

1. A device for removing oil from an operative's hand comprising a pair of spacedly arranged wiper blades connected at their bottoms and sides by means defining a receptacle therebetween, the upper and wiping edges of said blades being differently configured, said blades being relatively closely positioned and the space between the wiping edges thereof being unobstructed, so that a member may be wiped across both of said blades in one continuous wiping motion, a trough on the exterior surface of one of said pair of blades, and a communicating passage between said trough and said receptacle, above the bottom of said receptacle whereby the oil wiped by said blades will collect in said receptacle.

2. A device for removing oil from an operative's hand comprising a pair of wiper blades, the upper and wiping edges of said blades being differently configured, said blades being relatively closely positioned and the space between the wiping edges thereof being unobstructed, so that a member may be wiped across both of said blades in one continuous wiping motion, a first wall secured between the interior surfaces of each of said blades, side walls between said blades defining, with said blades and said first wall, a receptacle, a trough on the exterior surface of one of said pair of blades, and a communicating passage between said trough and said receptacle above the bottom of said receptacle, whereby the oil wiped by said blades will collect in said receptacle.

3. In the device of claim 1, a third wiper blade connected to the exterior surface of the other of said pair of blades at its bottom and sides by means defining an additional trough therebetween, and a communicating passage between said additional trough and said receptacle.

4. In the device of claim 2, a third wiper blade connected to the exterior surface of the other of said pair of blades at its bottom and sides by means defining an additional trough there-

between, and a communicating passage between said additional trough and said receptacle.

5. A device for removing oil from an operative's hand comprising a pair of spacedly arranged wiper blades connected at their bottom and sides by means defining a receptacle therebetween, the upper and wiping edges of said blades being differently configured, said blades being relatively closely positioned and the space between the wiping edges thereof being unobstructed, so that a member may be wiped across both of said blades in one continuous wiping motion, a trough on the exterior surface of one of said pair of blades, and said one of said pair of blades having an orifice therethrough above the lower surface and within the limits of said trough and above the bottom of said receptacle, whereby the oil wiped by said blades will collect in said receptacle.

6. A device for removing oil from an operative's hand comprising a pair of wiper blades, the upper and wiping edges of said blades being differently configured, said blades being relatively closely positioned and the space between the wiping edges thereof being unobstructed, so that a member may be wiped across both of said blades in one continuous wiping motion, a first wall secured between the interior surfaces of each of said blades, side walls between said blades defining, with said blades and said first wall, a receptacle, a trough on the exterior surface of one of said pair of blades, and said one of said pair of blades having an orifice therethrough above the lower surface and within the limits of said trough and above the bottom of said receptacle, whereby the oil wiped by said blades will collect in said receptacle.

7. In the device of claim 5, a third wiper blade connected to the exterior surface of the other of said pair of blades at its bottom and sides by means defining an additional trough therebetween, said other of said pair of blades having an orifice therethrough above the lower surface and within the limits of said additional trough.

8. In the device of claim 6, a third wiper blade connected to the exterior surface of the other of said pair of blades at its bottom and sides by means defining an additional trough therebetween, said other of said pair of blades having an orifice therethrough above the lower surface and within the limits of said additional trough.

9. A device for removing oil from an operative's hand comprising three spacedly arranged wiper blades connected to one another by means defining a receptacle between a first and second of said blades and a trough between the second and third of said blades, the upper and wiping edges of at least two of said blades being differently configured, said blades being relatively closely positioned and the wiping edge of one of said first and third blades being out of line with the wiping edges of the other two of said blades, the spaces between the wiping edges of said second blade and each of said first and third blades being unobstructed, so that a member may be wiped across said second blade and either of said first and third blades in one continuous wiping motion, and a communicating passage between said trough and said receptacle above the bottom of said receptacle, whereby the oil wiped by said blades will collect in said receptacle.

10. In the device of claim 9, an additional trough on the exterior of said first blade, and a communicating passage between said additional trough and said receptacle.

11. A device for removing oil from an operative's hand comprising three spacedly arranged wiper blades connected to one another by means defining a receptacle between a first and second of said blades and a trough between said second and third blades, the upper and wiping edges of at least two of said blades being differently configured, said blades being relatively closely positioned and the wiping edge of one of said first and third blades being out of line with the wiping edges of the other two of said blades, the spaces between the wiping edges of said second blade and each of said first and third blades being unobstructed, so that a member may be wiped across said second blade and either of said first and third blades in one continuous wiping motion, said second blade having an orifice therethrough defining a communicating passage between said trough and said receptacle above the bottom of said receptacle, whereby the oil wiped by said blades will collect in said receptacle.

12. In the device of claim 11, an additional trough on the exterior of said first blade, said first blade having an orifice therethrough defining a communicating passage between said additional trough and said receptacle.

13. In a device for removing oil from an operative's hand comprising a pair of spacedly arranged wiper blades, one of the blades having an edge line-shaped to fit across the palm or back of the hand and the other of said blades having an edge provided with a plurality of laterally spaced concave recesses adapted to fit part-way around individual fingers of the hand, the lateral spacing of the concave recesses corresponding to lateral spacing of the fingers of the operative's hand, the said pair of blades being spacedly arranged along a line extending transversely to the edges of the blades and hence in the direction of a hand scraping operation, whereby the operative's hand may be moved in one sweep in oil wiping contact with the palm or back scraping against the line-shaped edge of the first blade and with the fingers scraping against the recessed edge of the second blade, the improvement which comprises said blades being connected at their bottom and sides by means defining a receptacle, a trough on the exterior of one of said blades, and a communicating passage between said trough and said receptacle above the bottom of said receptacle, whereby the oil wiped by said blades will collect in said receptacle.

14. In a device for removing oil from an operative's hand comprising a pair of spacedly arranged wiper blades, one of the blades having an edge line-shaped to fit across the palm or back of the hand and the other of said blades having an edge provided with a plurality of laterally spaced concave recesses adapted to fit part-way around individual fingers of the hand, the lateral spacing of the concave recesses corresponding to lateral spacing of the fingers of the operative's hand, the said pair of blades being spacedly arranged along a line extending transversely to the edges of the blades and hence in the direction of a hand scraping operation, whereby the operative's hand may be moved in one sweep in oil wiping contact with the palm or back scraping against the line-shaped edge of the first blade and with the fingers scraping against the recessed edge of the second blade, the improvement which comprises said blades being connected at their bottom and sides by means defining a receptacle, a trough on the ex-

terior of one of said blades, and said one of said blades having an orifice therethrough above the lower surface and within the limits of said trough and above the bottom of said receptacle, whereby the oil wiped by said blades will collect in said receptacle.

15. In a device for removing oil from an operative's hand comprising three spacedly arranged wiper blades, one of the blades having an edge line-shaped to fit across the palm of the hand, another of the blades having an edge line-shaped to fit across the back of the hand, and the third blade, positioned between the first and second blades, having an edge provided with a plurality of laterally spaced concave recesses adapted to fit part-way around individual fingers of the hand, the lateral spacing of the concave recesses corresponding to the lateral spacing of the fingers of the operative's hand, the said three blades being spacedly arranged along a line extending transversely to the edges of the blades and hence in the direction of a hand scraping operation, whereby the front of the operative's hand may be moved in one sweep in oil wiping contact first with the palm scraping against the line-shaped edge of the first blade followed by the fingers scraping against the recess-shaped edge of the third blade, and then so that the back of the operative's hand may be moved in a return sweep in oil wiping contact first with the back of the hand scraping against the line-shaped edge of the second blade followed by the fingers scraping against the recess-shaped edge of the third blade, the improvement which comprises said blades being connected at their bottoms and sides by means defining a receptacle between one and another of said blades and a trough between said other and yet another of said blades, said another blade having an orifice therethrough defining a communicating passage between said trough and said receptacle above the bottom of said receptacle, whereby the oil wiped by said blades will collect in said receptacle.

16. In the device of claim 15, an additional trough on the exterior of said first blade, said first blade having an orifice therethrough defining a communicating passage between said additional trough and said receptacle.

17. A device for removing oil from an opera-

tive's hand comprising a pair of spacedly arranged wiper blades and walls connecting said blades, said walls being shaped to define an oil deposition receptacle, the upper and wiping edges of said blades being differently configured, said blades being relatively closely positioned and the space between the wiping edges thereof being unobstructed, so that a member may be wiped across both of said blades in one continuous wiping motion, and orifices connecting the inner surface of one of said blades and the outer surface of said one of said blades communicating with the interior of said receptacle.

18. A device for removing oil from an operative's hand comprising a pair of spacedly arranged wiper blades and walls connecting said blades, said walls being shaped to define an oil deposition receptacle, the upper and wiping edges of said blades being differently configured, said blades being relatively closely positioned and the space between the wiping edges thereof being unobstructed, so that a member may be wiped across both of said blades in one continuous wiping motion, and orifices connecting the inner and outer surfaces of said blades communicating with the interior of said receptacle.

19. The device of claim 17, in which a third wiper blade is connected to the outer surface of one of said pair of wiper blades below the point at which said outer surface communicates with the interior of said receptacle.
